Attorney.

UNITED STATES PATENT OFFICE.

EDWARD D. WOODS, OF CLEVELAND, OHIO, ASSIGNOR TO KOREN MANUFACTURING COMPANY, OF CLEVELAND, OHIO.

TOOL-HOLDER.

1,205,307.

Specification of Letters Patent. Patented Nov. 21, 1916.

Application filed June 15, 1916. Serial No. 103,721.

To all whom it may concern:

Be it known that I, EDWARD D. Woods, a citizen of the United States, and resident of Cleveland, in the county of Cuyahoga and State of Ohio, have invented certain new and useful Improvements in Tool-Holders, of which I hereby declare the following to be a full, clear, and exact description, such as will enable others skilled in the art to 10 which it appertains to make and use the same.

The objects of the invention are to provide a tool holder in two portions, one slideable upon the other, whereby the force of a 15 sudden blow can be applied to the work.

The inner member contains a tapered socket for the tool in which a chisel of any size or shape can be securely held, and which projects from the outer member. The 20 outer member is provided with a weighted head which is preferably shaped to form a hammer and thereby increase the usefulness of the tool, and also comprises a handle for the manipulation of the tool.

25 The mode of construction is illustrated in the accompanying drawings and specifically pointed out in the claims.

In the accompanying drawings Figure 1 is a perspective view of the device showing 30 a chisel inserted in the socket of the inner member; Fig. 2 is a perspective view of the device showing the inner or socket containing member; Fig. 3 is a transverse section of the tool; Fig. 4 is a longitudinal section 35 showing in dotted lines a tool inserted transversely thereof and employed to receive the shock of the outer member to loosen the taper shank of the tool in the socket, so that it can be easily withdrawn. Fig. 5 is a partial longitudinal section of the device.

In these views A is the outer member or sleeve, in which the inner member B is inserted. The inner member consists of an elongated fork, the sides b, b, of which are 45 parallel and are spaced apart so as to engage the sides of the guide flanges a, a, within the sleeve A. These flanges give a rectilinear movement to the socket member and tool and prevent rotary movement of the socket member. The walls of a socket B' rigidly connect the sides of the fork together at one end. This member is preferably constructed of three portions welded or riveted to the sides of the socket portion, 55 which project at c, c, on both sides where

they can be rapped sharply by the reinforced end of the sleeve member. An inwardly projecting rivet R in the inner end of one of the arms of the fork engages the transverse bar R' at the end of the sleeve 60 and prevents the fork and socket from escaping. Opposite holes S, S, in the sleeve permit of inserting and heading over this rivet. In use the hammer head D furnishes a handle by which the outer sleeve is held 65 firmly while the hand guides the chisel. When the tool is properly placed in the work the sleeve can be drawn out and returned so as to give a sharp blow to the tool, thus enabling the operator to cut deeper and 70 more quickly into the work, and at a slighter expenditure of energy than would be possible by hand alone. The force of the blow can also be nicely gaged and be quickly repeated when light and the manipulation 75 thereof is quickly learned. It is adapted for use in fine carving or tenon work of carpenters, and through a long range of work wherever a direct and quickly operated blow is to be delivered.

An important feature of the invention is found in the forked construction of the inner member which permits the insertion of a tool dislodging means such as another chisel, through the opening between the 85 sides of the fork. This receives the blow from the sleeve and transmits it to the projecting end E of the taper shank of the tool and thus easily loosens it from the taper socket.

Having described the invention what I claim as new and desire to secure by Letters Patent is:

1. In a tool, a forked member, and a sleeve member slidably movable thereon, a tool 95 socket in the outer end of the forked member, said socket opening into the space between the forks of said forked member, and a weighted head for the sleeve member, the opening between the sides of the forked 100 member permitting the insertion of a tool dislodging means adapted to receive the blow of the sleeve member.

2. In a tool, a forked member, and a non 105 rotatable sleeve member slidably movable thereon, a tool socket in the outer end of the forked member, said socket opening into the space between the forks of said forked member, and a weighted head for the sleeve member, the opening between the sides of the 110

forked member permitting the insertion of a tool dislodging means adapted to receive the blow of the sleeve member, said weighted head serving as a handle for withdrawing the sleeve member.

3. In a tool, a forked member, a weighted sleeve member slidably movable thereon, a tool socket in the outer end of said forked member, guides in said sleeve member for the sides of said forked member, said guides preventing the rotation of said socket member in said sleeve member, and means for preventing the escape of the forked member from the sleeve member.
4. In a tool, a forked member, a sleeve member slidably movable thereon, a tool socket in the outer end of said forked member, said tool socket opening into the space

between the forks of said forked member, said tool socket provided with lateral projections in the path of movement of said sleeve member, the opening between the sides of the forked member permitting the insertion of a tool dislodging means adapted to receive the blow of the sleeve member and 25 guide members on the inner walls of said sleeve member positioned between the said forks of the socket member to prevent rotation thereof in said sleeve member.

In testimony whereof, I hereunto set my 30 hand this 3rd day of May 1916.

EDWARD D. WOODS.
